(57) **CLAIM**

The ornamental design for a bed assembly, as shown and described.

DESCRIPTION

FIG. 1 is a perspective view of the bed assembly of the present invention

FIG. 2 is a front elevational view of the bed assembly of FIG. 1;

FIG. 3 is a rear elevational view of the bed assembly of FIG. 1;

FIG. 4 is a top view of the bed assembly of FIG. 1;

FIG. 5 is a bottom view of the bed assembly of FIG. 1

FIG. 6 is a left side elevational view of the bed assembly of FIG. 1;

FIG. 7 is a right side elevational view of the bed assembly of FIG. 1;

FIG. 8 is a perspective view of the bed assembly of the present invention in accordance with an alternative embodiment of the bed assembly;

FIG. 9 is a front elevational view of the bed assembly of FIG. 8;

FIG. 10 is a rear elevational view of the bed assembly of FIG. 8;

FIG. 11 is a top view of the bed assembly of FIG. 8;

FIG. 12 is a bottom view of the bed assembly of FIG. 8;

FIG. 13 is a left side elevational view of the bed assembly of FIG. 8;

FIG. 14 is a right side elevational view of the bed assembly of FIG. 8;

FIG. 15 is a perspective view of the bed assembly of the present invention in accordance with another alternative embodiment of the bed assembly;

FIG. 16 is a front elevational view of the bed assembly of FIG. 15;

FIG. 17 is a rear elevational view of the bed assembly of FIG. 15;

FIG. 18 is a top view of the bed assembly of FIG. 15;

FIG. 19 is a bottom view of the bed assembly of FIG. 15;

FIG. 20 is a left side elevational view of the bed assembly of FIG. 15; and,

(Continued)

FIG. 21 is a right side elevational view of the bed assembly of FIG. 15.

The portions drawn in broken lines depict portions of the article and form no part of the claimed design.
